UNITED STATES PATENT OFFICE.

ULYSSES L. COLLINS, OF SAN DIEGO, CALIFORNIA.

ELECTRIC CLOCK.

Application filed October 12, 1922. Serial No. 594,146.

To all whom it may concern:

Be it known that I, ULYSSES L. COLLINS, a citizen of the United States, and a resident of San Diego, county of San Diego, State of California, have invented a new and useful Electric Clock, of which the following is a specification.

The present invention relates to improvements in clocks and has particular reference to a clock actuated by electrical means. The particular object of the invention is to provide a self-winding clock whereby is meant a clock that will close an electric circuit whenever the weight actuating the same reaches a position where it becomes inactive. The closing of the circuit energizes an electro-magnet which latter attracts an armature and through the action of the armature returns the weight to its initial position. A further object of the invention is to provide separate equalizing means which cooperating with the weight moving along a circular path tends to render the resulting force applied to drive the mechanism equal throughout the operation. Further objects and advantages of my devices will appear as the specification proceeds.

With these objects in view I have shown the preferred form of my invention in the accompanying drawings in which Figure 1 represents a front view of the clock mechanism, Figure 2 a side view of the same, looking at it from the righthand side, Figure 3 a side view of the same, looking at it from the lefthand side, Figure 4 a sectional detail view taken along line 4-4 of Figure 3, Figure 5 a vertical sectional detail view taken along line 5-5 of Figure 4, Figure 6 a detail view showing a pawl and ratchet engagement, Figure 7 a detail view of the power shaft and its support and Figure 8 a wiring diagram. While I have shown only the preferred form of the invention I wish to have it understood that various changes or modifications may be made within the scope of the claims hereto attached without departing from the spirit of the invention.

The two vertical plates (1) and (2) between which the working mechanism of my clock is supported are held in spaced and parallel relation to each other by means of the spacing members (3). The rear plate (1) is supported on preferably three pins (4) extending from base plates (6) which latter are secured to the main rear support

(7) by any suitable means as by the screws (8). The rear plate (1) engages the lower pins (4) by means of a transverse plate (9) provided with vertical slots (11) adapted to slide on a reduced portion of the pins and to be held in place by means of nuts (12). Near its upper end the rear plate (1) is provided with a slanting lateral slot (13) adapted to slidably engage a reduced portion of the upper pin (4) and to be held in place by the nut (14). This means of fastening the plate (1) to the main support allows of the removal of the whole working mechanism by merely unloosening the nuts (12) and (14) respectively and by pushing the top of the plate (1) sideways.

The working mechanism of my clock is driven from the shaft (16) and does not differ essentially from similar devices now on the market. A large gear wheel (17) is loosely mounted on the shaft and rotated from the latter by means of a spring (18) secured on a collar (19) which latter is fixed to the shaft, the spring engaging and pushing a pin (21) rising from the side of the gear wheel (17). The latter meshes with a pinion (22) on the shaft (23) carrying the second hand (24). The motion of the latter shaft is regulated by the escapement (26) shown in Figure 1 comprising the toothed wheel (27) and the pallet (28) on the shaft (29) supported between the two plates (1) and (2) and the pendulum (31) supported on the upper pin (4) by means of a spring (32). A pinion (33) rigidly secured to the gear wheel (17) meshes with a gear wheel (34) on the shaft (36) to the end of which is secured the minute hand (37). The hour hand (38) is fastened on a sleeve (39) loosely mounted on the shaft (36) and receiving rotary motion at a reduced rate from the latter shaft through the pinion (41) meshing with a gear wheel (42) and the pinion (43) meshing with the gear wheel (44).

The principal feature of the present invention consists in the drive means for the shaft (16). The latter as shown in Figure 7 consists preferably of two parts, one part (46) being supported between the rear plate (1) and a bracket (47) and terminating in a reduced extension (48) which serves as a journal for one end of the part (49), the other end of which rests in the front plate (2). On the part (46) of the shaft (16) is supported a bell-crank lever (51), one arm of which carries a weight (52) while the

other end is provided with a lateral projection (53). It will be seen from Figure 5 that the weight (52) when occupying the position indicated in said figure will have a tendency to cause the shaft (46) to rotate until the weight has fallen to substantially the lowest position it may obtain in following a circular path around the axis of the shaft (46). It will also be seen that the force applied by the weight varies according to its particular position. Travelling along a circular path the weight will gain in momentum as it approaches the horizontal center line. For the best operation of the clock it is desirable however that the force brought to bear by the weight should be as uniform as possible and to obtain this result I provide a spring (55) which cooperates with the weight in turning the shaft. The spring is positioned in such a manner as to pull downward and its tension is most intense when the weight is in its upper most position while its tension slackens as the weight moves downward. We thus have two forces tending to turn the shaft (46) one increasing in force and the other decreasing and the two forces should be adjusted in such a manner that the resulting force is uniform throughout. The bell crank lever (51) is rigid on the shaft (46) and the rotary motion of the latter shaft is transmitted to the shaft (49) by means of the pawl (54) pivotally secured to the weight as shown at (56) and the ratchet (57) fixed to the shaft (49), the pawl and ratchet being held in engagement by a spring (58). The latter is supported on a pin (59) projecting from the side of the weight (52) and is held in yielding contact with the flat portion of the pawl forcing the latter normally in contact with the teeth of the ratchet but allowing the same at the same time to be turned at right angles to its operative position and to come to rest in that position as shown in dotted lines in Figure 6. The ratchet is prevented from turning in the opposite direction by means of a dog (61) supported on a small shaft (62).

When the weight reaches its lowermost operative position the other arm (64) of the bell crank lever makes contact with a vertical rod (66) bent at the lower end as shown at (67) Figure 1 and secured to the armature (68) pivotally supported between the lips (69) of a brass plate (71) secured to the lower end of two electro-magnets (72) which latter are supported by a bracket (73) by means of two screws (74). The armature is secured on its pivot in such a manner that it normally falls away from the electro-magnets into the slanting position shown in Figure 1. The upper rear edge (76) striking the bottom of the brass plate (71) and thereby preventing the armature from going beyond this position. As will be

shown later the bell crank lever (51) and the vertical rod (66) are included in the circuit forming the electro-magnet and the latter circuit is closed when the lower arm of the bell crank lever strikes the rod (66), that is when the weight is in its lowermost working position. When the electro-magnets become energized they attract the armature and cause the same to swing on its pivot (69) whereby the vertical rod (66) is pushed violently against the projection (53) of the lower arm of the bell crank lever throwing the same forward and returning the weight to its initial position. Particular attention is called to the engagement between the vertical rod (66) and the bell crank lever arm (64). The engagement is such that at first, that is during the initial part of the motion of the armature, an intermediate portion of the rod (66) engages the projection (53) which latter is provided at the end of the lower arm, thus securing a favorable leverage for the armature at the beginning. As the armature approaches the electro-magnet the magnetic force attracting the same becomes stronger and the point of attack of the rod (66) on the lever arm is changed so that during the latter part of the stroke a projection (67) at the extreme end of the rod engages a point of the lever near its fulcrum whereby the final momentum of the weight is increased, which throws the weight back to its initial position and breaks the circuit.

The wiring for my device will be readily understood from the wiring diagram shown in Figure 8. A wire (77) leads from a suitable source of power as the battery (78) to the screw (8) which is through the plate (1) and the shaft (46) electrically connected with the bell crank lever (51). When connection has been established between the lower arm of the bell crank lever and the vertical rod (66) a current passes from the lever through the rod to the armature (68) and from there through the windings (79) of the electro-magnet and through the wire (81) to the plate (9) which is separated from the remainder of the working mechanism by means of the insulating material (82). A wire (83) connecting the pin (4) which is in electrical contact with the plate (9) to the battery (78) completes the circuit. The electro-magnet is preferably shunted by a non-inductive resistance (84) for the purpose of eliminating the spark when the contact is broken.

The operation of the device will be readily understood from the foregoing description. Beginning with the position shown in Figure 5 the weight (52) tends to rotate the shaft (46) and is assisted in this tendency by the spring (55), the two forces cooperating to obtain a uniform motion as described hereinbefore. As the

weight reaches a predetermined position the projection (53) at the lower end of the lever arm (64) strikes the rod (66) and thereby completes the circuit for the electro-magnets. The armature is attracted and the rod (66) first engaging the projection (53) with an intermediate portion of the rod and thereafter engaging an intermediate portion of the lever arm with its extreme end throws the latter forward and the weight back to its initial position allowing the latter to resume its action. In this manner the clock is kept running as long as the battery is sufficiently strong to actuate the armature and through the same the weight (52). The particular strength of the battery is of little importance the only difference being that a weak battery may not throw the weight upward quite as high as a strong battery and that as a consequence the periods for the operation of the weight become shorter which however need not interfere with the time keeping qualities of the clock.

Particular attention is called to the fact that due to the construction of my device the whole working mechanism may be removed without the necessity of disconnecting any wires, because the electrical connections are broken by merely removing the plate (1) from the supporting pins (4).

It should also be mentioned that the manner in which the circuit is broken each time the weight is actuated by the armature of the electro-magnet offers a distinct advantage in so far as the point where the circuit is broken does not coincide with the point where the circuit is closed and the latter point therefore remains unaffected by any spark that might occur due to the breaking of the circuit. As has been described, the circuit is closed by an intermediate portion of the rod (66) engaging the projection (53) of the bell crank lever, while the circuit is broken only after the end of the rod (66) has engaged an intermediate portion of the bell crank lever and any sparking that might take place would occur at the latter point of engagement. The breaking of the circuit is caused by the momentum of the weight which continues its upward motion on the arc of a circle after the rod (66) has come to a stop.

The particular construction of the pawl

(54) facilitates the assembling of the clock since it may be turned into the position shown in dotted lines in Figure 6 so as not to interfere with the insertion of the ratchet wheel (57).

I claim:

1. Means for actuating a clock, comprising a working mechanism, a shaft for driving the same having a lever arm thereon, a weight at the free end of the arm adapted to rotate the shaft and a spring cooperating with the weight disposed so as to decrease in tension as the weight gains in effectiveness due to the circular curve described by the same. 60

2. Means for actuating a clock, comprising a working mechanism, a shaft for driving the same having a lever arm thereon, a weight at the free end of the arm adapted to rotate the shaft and a spring cooperating with the weight disposed so as to decrease in tension as the weight gains in effectiveness due to the circular curve described by the same, and electrical means for returning the weight to its initial position after its force is expended adapted to simultaneously place the spring under tension. 75

3. In a clock of the character described, two plates disposed in spaced relation to one another having a working mechanism supported between the same, and means for supporting one of the plates comprising two parallel lower pins and one upper pin disposed centrally above the two pins, 90 two vertical slots being associated with the plate adapted to slidably engage the two lower pins and a slanting lateral slot being provided in the plate adapted to engage the upper pin on a combined lateral and 95 downward motion.

4. In a device of the character described, a pawl and ratchet engagement comprising two coaxial shafts, a lever arm mounted on one of the shafts and a ratchet wheel 100 on the other one, a pawl pivotally supported on the lever arm adapted to engage the ratchet teeth having flat surfaces surrounding its pivot, and a spring adapted to bear on one of said flat surfaces so as to hold the pawl in engagement with the ratchet, the spring allowing the pawl to be swung into and come to rest in a position at an angle to its operative position. 105

ULYSSES L. COLLINS.
